CLAIM

The ornamental design for a floor for nestable crate with handle, as shown and described.

DESCRIPTION

FIG. 1 is a side elevational view of a floor for nestable crate in accordance with our new design, the opposite side being a mirror image thereof;

FIG. 2 is an end elevational view of the floor for nestable crate of FIG. 1, the opposite side being a mirror image thereof;

FIG. 3 is a top plan view of the floor for nestable crate of FIG. 1;

FIG. 4 is a bottom plan view of the floor for nestable crate of FIG. 1;

FIG. 5 is a cross sectional view of the floor for nestable crate taken along line 5—5 of FIG. 3;

FIG. 6 is a cross sectional view of the floor for nestable crate taken along line 6—6 of FIG. 3;

FIG. 7 is a cross section of the floor for nestable crate taken along line 7—7 of FIG. 3;

FIG. 8 is a cross section of the floor for nestable crate taken along line 8—8 of FIG. 3; and,

FIG. 9 is a cross section of the floor for nestable crate taken along line 9—9 of FIG. 3.

The broken line showing in FIGS. 1-6 of the walls of a nestable crate with handle is for illustrative purposes only and forms no part of the claimed design.
